UNITED STATES PATENT OFFICE.

HOWARD EMERY MORINE, OF NAHANT, MASSACHUSETTS, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,196,802.

Specification of Letters Patent.

Patented Sept. 5, 1916.

Application filed February 10, 1912. Serial No. 676,753.

To all whom it may concern:

Be it known that I, HOWARD EMERY MORINE, a citizen of the United States, residing at Nahant, in the county of Essex 5 and State of Massachusetts, have invented certain new and useful Improvements in and Relating to Filing Appliances, of which the following is a specification.

This invention relates to filing appliances 10 which are adapted for supporting papers, bills, slips or documents in a manner permitting them to be easily and accurately filed, inspected or removed.

For the purpose of illustration, I have, in 15 the accompanying drawings, shown and herein described one form of appliance embodying my invention.

Figure 1 is a front elevation of a filing appliance embodying my invention, one carriage and the set of holders thereon being 20 shown in position whereby the latter can be operated. Fig. 2 is an elevation looking toward the right in Fig. 1, a portion of the casing being broken away. Fig. 3 is a horizontal sectional view on the line 3—3 of Fig. 2. Fig. 4 is a perspective view of one 25 of the carriages and the rotatable member or carrier thereon. Fig. 5 is a view similar to Fig. 4 showing the rotatable member 30 moved to operative position. Fig. 6 is a fragmentary perspective view of the carriage and rotatable member, the former being broken away and the latter detached or slightly elevated to illustrate its operation. Fig. 7 is a cross sectional view of the parts 35 shown in Fig. 6 in normal position.

In the drawings, 1 indicates a support having a platform 1^a. This support may consist of a suitable frame comprising a 40 main section 1^b and a superposed section 1^c mounted on the rear portion of the platform 1^a. The main section is provided with a top, which in the illustrated embodiment of the invention serves as the platform 1^a, the purpose of which will be later described. The 45 main section 1^b preferably comprises a bottom wall 1^d, side walls 1^e and a rear wall 1^f, and supported above the floor by legs 1^g. By this form of construction accommodation is 50 made for a plurality of drawers 1^h and trays 1ⁱ, the former being adapted for supplies and the latter for indexes. The drawers 1^h and trays 1ⁱ may be arranged in tiers, as shown, and separated by a partition 1^k,

which also assists in supporting the platform 1^a.

The superposed section 1^c preferably comprises a rear wall 1^m, extending from end to end of the platform 1^a at or near its rear edge, side walls 1ⁿ, and a top or cover 1°. 60 I may also provide the superposed section 1^c with a plurality of partitions 1^p, spaced from each other, for dividing it into compartments 1^q, each adapted for receiving and inclosing a filing unit 2. The superposed section 1^c is of a length from front to rear to receive and inclose a filing unit when placed endwise therein. Being open at its front, each unit 2 may be moved forwardly 65 on the platform 1^a, or from within the superposed section 1^c, for operation, as will be presently set forth.

Each filing unit 2 comprises a carriage 3 movable in an endwise direction forwardly and rearwardly on the platform 1^a, a carrier or supporting member 4 rotatably mounted on the carriage 3, and a set of pivoted holders 5, supported on the carrier 4. The carriage 3 may consist of an open rectangular frame 3^a and a cross plate 3^b. 80 At its forward end it is provided with a cross member 3^c which serves as a grip or handle whereby the carriage can be moved forwardly on the platform 1^a to operative position and returned to normal position 85 within the supersection 1^c. The upper face of this member is preferably flat and serves as a rest for those holders which are operated to the horizontal position, as shown in dotted lines in Fig. 2. 90

3^d indicates suitable rollers or wheels for the carriage 3 and adapted to tracks or ways 1^{a'} on the platform 1^a to guide it thereon. These ways 1^{a'} preferably comprise 95 grooves formed in the platform and extending substantially from its front edge to its rear edge. The grooves 1^{a'} may be of such length that their opposite ends form stops to limit the movement of the carriage in either direction.

The carrier 4 preferably consists of a base 4^a, which may be an open rectangular frame, provided with a cross plate 4^b, and adapted to support the adjacent set of holders 5, and a back or rear wall 4^c arranged 105 perpendicular to one longitudinal side edge of the base 4^a. The back 4^c serves as an abutment for the rearmost holder 5. The

back 4^b may comprise a skeleton frame having two or more vertical members 4^c and a cross member 4^d.

4^e indicates braces extending from the outermost vertical members diagonally downward and connected to the base 4^a at or near its opposite side edge.

4^f indicates a pair of devices spaced from each other, and arranged to removably support the set of holders on the carrier 4.

The holders 5 preferably comprise a series of frames of uniform size, each having a back 5^a to which clip devices 5^b are secured, and suitable spacing ribs 5^c.

15 The holders 5 are preferably pivotally connected or geared together in a pack by connections 5^d. These connections permit the holders to swing relative to each other, from a substantially vertical to a substantially horizontal position and vice versa and operate during such operations to move the lower or hinged ends of the upright holders forwardly and rearwardly, and also to raise and lower the upright holders bodily. As 20 shown in the drawings, the pivot pins for the frontmost holder 5 are removably mounted in bearings formed in the devices 4^f which thus serve as the pivot bearings for said front holder 5. The devices 4^f also 25 serve as a support for the front end of a series of holders which rest by gravity against the back 4^b when in normal position.

30 6 indicates a guide member for guiding the rearmost holder 5 in its up and down movements, as the holders forward thereof are operated. This member is supported by the back 4^b, it being connected to a socket member 6' which in turn is fixed to the cross member 4^a. In the operative position of 35 said guide (see dotted lines in Fig. 2), it is preferably inclined upwardly and forwardly in order that the upper edge of said rear holder, and those holders which may be in the upright position, may be moved forwardly and rearwardly during their up and down movements. At or near its free end, the guide 6 is provided with a catch or stop 6^a with which the rearmost holder 5 engages when elevated to its highest position. 40 50 Through the engagement of the rear holder with the catch 5^a, said holder will be locked against operation to the horizontal position.

55 The guide 6 is preferably pivoted in the socket member 6' at 6^b, whereby it is free to swing downwardly under the influence of gravity and rest on the upper or free edges of the holders 5 when all of the latter have been returned to normal position. In this latter position of the guide 6, its catch 6^a 60 will lie in the path of the front holder 5 and thus lock it and all of the holders against operation. In order to release the front holder, the free end of the guide is pressed upwardly slightly, after which the 65 front holder may be swung forwardly and

downwardly. This operation will cause the remaining holders to rise which in turn will elevate the guide to its operative position.

6^c indicates a stop against which the guide bears during the operation of the holders.

70 Interposed between the carriage 3 and carrier 4 is a turntable 7, which permits the carrier 4 to be rotated relative to the carriage 3 in order to arrange the holders 5 in position for operation. The turntable 7 75 preferably comprises a pair of bearing plates 7^a, 7^b, each of circular form, and secured to the cross plates 3^b, 4^a', of the carriage and carrier, respectively. One of said plates, 7^b, is provided with a pin 7^c which 80 fits a socket bearing 7^d formed in the other plate, 7^a, the pin 7^c and bearing 7^d forming the shaft or pivot for the turntable 7.

85 As will be understood from the drawings when a filing unit 2 is in inoperative position and arranged within its compartment 1^e, the carrier 4 thereof is in line with its carriage 3; but when the filing unit 2 is drawn forward on the platform 1^a and the carrier 4 thereof is rotated or swung around 90 on the turntable 7 to the operative position, that is, so that the holders 5 face the operator, the said carrier is arranged substantially at right angles to its carriage 3. In order that the carrier 4 can be quickly positioned either in line with its carriage ready to be shifted out of the way or within its compartment 1^e or at right angles thereto, I provide suitable means which limit the movements of the carrier in either direction. 95 These means preferably comprise a recess or cutaway portion 7^e formed in the turntable plate 7^a the opposite end walls 7^e' of which serve as abutments or stops for a lug 7^f depending from the other turntable plate 7^b 105 and movable from end to end of the recess 7^e.

8 110 indicates shoes or bearing plates which are preferably provided on each carriage and arranged to be engaged by the opposite ends of the adjacent carrier 4. The shoes 8 serve to steady the carriers and holders on the carriage during the forward and rearward shifting of the units 2. They also prevent the carriers from rocking into engagement with or bearing on the rollers 3^d 115 and thus affecting the endwise movement of the carriages.

9 indicates automatically operating devices for locking the carriages in their forward position. One of these devices is preferably mounted on each carriage 3. It preferably comprises a bell-crank lever freely pivoted at 9^a to the rear end of an adjacent carriage. One arm 9^b of the lever 9 is relatively long and forms a weighted end 120 whereby said arm will normally swing downwardly to a substantially horizontal position under the influence of gravity. The other arm of the lever, indicated at 9^c, is relatively short and provided with a 125

130

turned over end 9^c which normally lies in the path of the carrier 4. As will be understood from Fig. 4 when the carrier 4 is swung into alinement with its carriage 3, it 5 will engage the turned-over end 9^c and swing the lever arm 9^b upwardly. In this position of the lever 9, the carriage may be moved forwardly and rearwardly on the platform 1^a. When a carriage is moved forwardly and the carrier thereon is rotated to 10 the operative position, the latter disengages the turned-over end 9^c of the lever arm 9^b, whereupon the weighted arm 9^b swings downwardly to a horizontal position with 15 its free end in front of an adjacent partition 1^b, (as shown in Figs. 1, 2 and 3) the latter operating as a stop and coöoperating with the lever to lock the carriage 3 in its forward position. If now the carrier 4 is 20 returned to its former position on the carriage, it will engage the turned-over end 9^c and swing the lever on its pivot, thus elevating the free end of the lever arm 9^b and releasing the carriage.

25 As will be clearly understood from Fig. 2 of the drawings, the carriage is maintained in its forward position on the platform by the engagement of its front rollers 3^d with the front end walls of the guide 30 grooves 1^a and the locking device 9. Hence, it is held stationary against all stresses incident to the operation of the holders 5.

It will be seen from the foregoing description that I have provided a filing appliance containing a plurality of filing units which can be nested together side by side in compact arrangement and occupying a minimum space, and that each unit can be moved, independently of the remaining 40 units, to and arranged in a position at substantially right angles to its nested position in order that its holders can be operated. The construction not only adapts the appliance to the accommodation of a large number 45 of filing spaces without a material increase in floor space, but on account of its compactness and simplicity, and the capability of each unit to be readily moved to an operative position, it lends itself to accuracy and speed of operation. In this 50 connection, it will be seen that the operator can stand centrally of the support and without shifting his position operate each unit at will.

55 Each set of holders may be removed from its carrier for storage in a place of safety. If desired, the holders and their carrier can be removed from the carriage together, the pin and socket connection between the carrier and carriage permitting their separation at will.

To those skilled in the art of making filing appliances of the class described, many alterations in construction and widely differing embodiments and applications of my

invention will suggest themselves, without departing from the spirit and scope thereof. My disclosures and the description herein are purely illustrative, and are not intended to be in any sense limiting.

70

What I claim is:—

1. The combination of a support and a filing unit bodily mounted thereon, the said unit comprising a carriage, a carrier mounted on the carriage to rotate on a vertical axis, and a series of pivoted holders on the carrier arranged to swing from upright to reclined position.

2. The combination of a supporting platform, a carriage movable on the platform, a carrier mounted on the carriage to rotate on a vertical axis, a series of pivoted holders mounted on said carrier, and means for locking the carriage on the platform effective when the carrier is rotated from normal position.

3. The combination of a carriage, a carrier provided with a back mounted on said carriage, pivotal means interposed between said carriage and the carrier permitting the latter to rotate relative to the carriage, and a series of pivoted holders on the carrier, the carriage and the back of the carrier serving as supports for the opposite end holders of the series.

4. The combination of a support, a carriage movable on the support, a carrier mounted on said carriage to rotate on a vertical axis, a series of pivoted holders on said carrier, pivotal means interposed between said carriage and the carrier, permitting the latter to rotate relative to the carriage, and stops carried by the pivotal means for limiting the rotative movement of the carrier in each direction.

5. The combination of a support, a carriage movable forwardly and rearwardly thereon, a set of holders, a carrier for said set of holders mounted on the carriage, means interposed between said carrier and carriage permitting the carrier and set of holders to be rotated relative to the carriage, and shoes on the carriage arranged to engage said carrier for steadyng it during the movement of the carriage.

6. The combination of a support, a plurality of sets of pivoted holders normally arranged in an inoperative position side by side on said support, means for independently carrying each set of holders and permitting it to be moved bodily into an operative position including a carriage movable on said support, and a carrier rotatably mounted on said carriage, and means for locking the carriage on the support effective when the carrier is rotated from normal position.

7. The combination of a support comprising a main section and a superposed section having a series of partitions for dividing

80

- said superposed section into compartments, a series of filing units, one for each of said compartments, bodily movable in an endwise direction on said main section into and out of said compartments, each of said units including a set of holders, and a device carried by each unit arranged to engage an adjacent partition for locking the unit in the operative position.
10. 8. The combination of a support comprising a main section and a superposed section having a series of partitions for dividing said superposed section into compartments, a series of filing units, one for each of said compartments, bodily movable in an endwise direction on said main section into and out of said compartments, each of said units including a set of pivoted holders arranged to swing from the vertical position to the horizontal position when the unit is positioned out of the adjacent compartment, and means carried by the unit for locking the holders in an upright position during the movements thereof into and out of said compartments.
15. 9. The combination of a support having a top or platform, a series of sets of holders normally arranged side by side on said top or platform, a carriage for each of said sets of holders permitting them to be independently shifted in an endwise direction on said top or platform, pivotal supports for the holders of each set permitting them to be operated from a vertical position to 35 horizontal position, and vice versa, and means for rotatably supporting each set of holders on its carriage, whereby they can be arranged at right angles thereto for operation, the forward end of the carriage 40 being provided with a rest for supporting the holders that are operated to the horizontal position.
20. 10. The combination of a support, a carriage movable thereon, a set of pivoted 45 holders, supporting carrying means for said set of holders rotatably supported on said carriage and permitting said set of

holders to be adjusted angularly thereon, and an element carried by the carriage for supporting the free ends of the holders 50 when they are operated.

11. The combination of a support having a top or platform, a series of sets of holders normally arranged side by side on said top or platform, a carriage for each of said sets of holders permitting them to be independently shifted in an endwise direction on said top or platform, pivotal supports for the holders of each set permitting them to be operated from a vertical position to 60 horizontal position, and vice versa, and means including a turntable for rotatably supporting each set of holders on an adjacent carriage, whereby they can be arranged at right angles thereto for operation, the 65 members of said turntable being provided with stops for limiting the rotatable movements of the set of holders in either direction.

12. The combination of a support 70 provided with a stop, a filing unit bodily movable forwardly and rearwardly thereon, the said unit comprising a carriage, and a set of holders, and a lever pivoted to said carriage and arranged to engage said stop for 75 locking the filing unit in its forward position.

13. The combination of a support, provided with a stop, a filing unit bodily movable forwardly and rearwardly thereon, the 80 said unit comprising a carriage, a set of holders, and means for swingably supporting the holders on said carriage, and a lever pivoted to said carriage and arranged to engage said stop for locking the filing unit 85 in its forward position, the operation of said lever being controlled by the swingable supporting means for the set of holders.

In testimony whereof I affix my signature in the presence of two witnesses.

HOWARD EMERY MORINE.
